ABSTRACT

A primary switch of a control circuit is closed to energize a motor and clutch to drive a carriage for relocating positive stops limiting travel of one or more thread guides and to energize a signalling device. The carriage and thread-guide stops are precisely positioned automatically by interposition of a preset blocking member between the source of a light beam, magnetic field or air jet of the signalling device and its signal receiver to open a secondary switch in the control circuit and thereby affect instantaneous deenergization of the motor and clutch and actuation of an auxiliary lock to prevent overtravel of the carriage on its feed screw. Alternatively, the clutch may be disengaged by a photoelectric counter responsive to the angle of rotation of the feed screw. Several signalling devices and receivers may be mounted on the carriage and connected in parallel to open sequentially secondary switches in the control circuit, in which case the primary switch is a sequential or stepping selector switch.

THREAD-GUIDE SETTING DEVICE FOR STRAIGHT-BAR KNITTING MACHINES

In the manufacture of garment components on a straight-bar knitting machine, particularly the manufacture of full-fashioned components in which the width transversely of the knitting frame is nonuniform, it is necessary to provide means for setting the thread-guide to the proper location for the desired width of pieces to be knit at the beginning of the knitting operation for each successive component. Such setting of the thread-guide has been performed mechanically by positive settable stops, chain and sprocket adjustment or cam surfaces, for example, to locate the thread guide accurately relative to the outermost needle to be operative at the beginning of the cycle for knitting a particular garment component.

If identical components are to be knit consecutively, it is merely necessary to return the thread guide to the same initial position for each component. If various dissimilar garment components are to be knit sequentially, such as the front, back and two sleeves of a full-fashioned pullover sweater, it is necessary to provide a thread-guide position control which will selectively locate the thread guide for the particular one of the components to be knit in a given step of a multiple-step cycle.

In order to eliminate resetting of the thread guide by an operator manipulating a hand crank relative to indexing means after completion of each component, various devices have been proposed or used employing a servomotor to reset the thread-guide-limiting means automatically.

One such device includes a carriage having a positive stop engageable by a microswitch carried by the thread guide. The carriage is repositioned by a feed screw driven by a servomotor. When the microswitch is actuated, the circuit to the motor is opened. Because the switching mechanism is dependent on a mechanical switch actuation, the switching time cannot be precisely determined. Also, because of the inertia of the motor shaft, overtravel of the carriage frequently results. In order to locate the carriage precisely, a ratch stop is provided. A slip clutch has been interposed between the servomotor and the carriage in order to isolate the inertial force of the servomotor from the positively-stopped carriage. With this known device controlled by a microswitch, it is possible to adjust the carriage automatically only in one direction, that is, from a smaller to a larger working width.

A different known device permits automatic adjustment of the thread-guide stops in opposite directions. Shortly before the carriage reaches the final position a disk clutch is released by a microswitch closed by the carriage. Closing of the microswitch actuates a relay to engage a cam follower roll with a cam. Such cam actuates a ratchet to terminate movement of the carriage upon reaching its proper position and to deenergize the servomotor. Simultaneously with the stopping of the carriage an index bolt is engaged with a feed-screw lock to hold the carriage to its proper position. Such a device does not stop the carriage precisely because of the difficulty of adjusting the cam accurately for the amount of inertial rotation of the feed screw after the clutch has been released.

All of the previously known thread-guide setting devices have used limit switches, the switching tolerance of which is not sufficiently precise to effect the fine settings necessary to locate the thread-guide at a particular operative edge needle location. In addition the influence of the inertial mass of the drive mechanism on the regulative distance of the carriage travel has not been sufficiently reduced.

Furthermore, neither of the devices discussed above nor any other known device permits automatic presetting for programming of the thread-guide setting mechanism for knitting a series of unlike pieces in succession, such as the four pieces required for a pullover sweater, namely, the front, the back and two sleeves, nor can the four-piece cycle be repeated automatically.

It is a principal object of the present invention to provide simple and economical mechanism for automatically positioning the thread guide of a straight-bar knitting machine at the beginning of the knitting cycle for each garment component.

It is a companion object to provide such mechanism which will set the thread guide with greater precision than has been possible heretofore. More particularly, it is an object to prevent overtravel of the positioning mechanism due to inertia of mechanical moving devices.

Another important object is to provide such setting mechanism which can be preset to position the thread guide for the beginning of knitting of successive unlike garment components automatically in proper sequence.

10 It is further an object to provide setting means for quickly, easily and accurately presetting the positioning mechanism corresponding to the position of the outermost needle operative to begin knitting of a given component, as well as corresponding to the size of such needle.

15 FIG. 1 is a top perspective of the thread-guide-positioning and position-signalling mechanism.

FIG. 2 is a diagram of the control circuit for the mechanism shown in FIG. 1.

20 FIG. 3 is a diagrammatic section through an alternate form of signalling mechanism and FIG. 4 is a diagrammatic plan of another form of signalling mechanism.

FIG. 5 is a top perspective of still a different type of signalling mechanism including a diagram of the control circuit actuated by such mechanism.

25 FIG. 6 is an enlarged detail of a modified component of the signalling device shown in FIG. 1.

FIG. 7 is a diagram of a modified control circuit operable to effect setting of the thread guide for the sequential knitting of unlike garment components.

30 FIG. 8 is a diagram of a control circuit different from that shown in FIG. 2.

In principle the control mechanism of the present invention can be used with any known drives for limiting movement of a thread guide in straight-bar knitting machines, such as by relocatable stops chain and sprocket adjustment, or cam surfaces. The invention is described herein in connection with a feed screw and carriage which is usually provided in straight-bar knitting machines for setting stops limiting movement of the thread guide.

35 In FIG. 1 only the thread-guide setting device for the left side of the knitting frame is shown and described in connection with its control mechanism. The setting device for the right side of the frame is identical and may be operated by the same control mechanism or by independent control mechanism of the same type.

40 A carriage 10 is mounted on feed screw 1 and a guide shaft 100 extends through the carriage to prevent its rotation about the feed screw. On the carriage 10 is mounted a bracket 101 for supporting one or more vertically adjustable stops 102. Such stops may engage or be engaged by a portion 103 of one or more thread guides to limit movement of such thread guides transversely of the knitting frame. A sprocket 11 on the feed screw 1 is driven through chain 110 and sprocket 111 by shaft 112 on one side of dog clutch 115. When the clutch is engaged, shaft 112 is connected to be driven by shaft 113 of the reversible servomotor 114.

45 A notched wheel 140 on the feed screw shaft is engageable by a lock bolt 14 having an end complementary to the wheel notches, such lock bolt being normally biased toward the wheel by spring 141. Wheel 140 and bar 14 constitute a lock to prevent inadvertent rotation of the feed screw. Pawls 12 and 13 are selectively engageable with ratchet wheels 120 and 130, respectively, to prevent rotation in a direction opposite that selected by the control mechanism. Selective engagement of one or the other pawl with its ratchet wheel is effected by its cam disk 121 or 131, which cam disk may be operated by the control circuit for motor 114 and clutch 115 or may be an independently-operated emergency brake for the feed screw.*

50 Also the pawls 12 and 13 may selectively engage with the ratchet wheels 120 and 130, respectively, to actuate the feed screw 1, the choice of pawl being effected by means of its cam disks 121 and 131, respectively, controlled by any known control device (not shown).

55 On the knitting machine frame 15 a track 150 is mounted by spacers 154. Such track supports signal-blocking member 16.

The track is calibrated so that the appropriate edge 160 or 161 of blocking member 16 can be preset to interrupt movement of carriage 10 in a position corresponding to a given position of the thread guide relative to the knitting frame. The blocking member is locked in its preset position by a catch 162 received in one of the notches 155 in the side of track 150.

A bracket 104 on carriage 10 carries a photoelectric cell 181 as an example of means for receiving a nonmechanical signal. A further bracket 18 on the carriage carries a light source 180 as an example of means for generating and emitting a nonmechanical signal, spaced above and located to direct a light beam onto photoelectric cell 181. The light source and cell, therefore, are fixed relative to each other, but are moved by carriage 10 relative to track 150. The blocking member 16 has a tongue 160, 161 extending beyond track 150 toward the carriage so that such tongue can be interposed between the light source 180 and photoelectric cell 181 to block the light beam by movement of the carriage.

For purposes of illustration, it will be assumed that the knitting machine is programmed to knit a particular garment component successively. Of which the left edge needle of the machine needle bed in its last row is closer to the knitting frame center than it is for its initial row of the previously completed component, so that the carriage 10 would be located to the right of signal-blocking member 16. The program for the knitting cycle would effect energization of the motor 114 and clutch 115 upon completion of the garment component. The motor shaft would rotate in a counter-clockwise direction as viewed from the left of FIG. 1, as set by motor direction switch 19 on frame 15, to move the carriage to the left toward blocking member 16. In this instance the light signal from the source 180 would be interrupted as soon as the right edge 160 of member 16 is interposed between the signalling means light source and photoelectric cell components 180, 181.

If the carriage were to be moved toward the center of the machine needle bed, the carriage would be located initially to the left of blocking member 16 and switch 19 would be set in its opposite position to reverse motor 114 for turning screw 1 in the counterclockwise direction to drive carriage 10 to the right of FIG. 1. In this instance the left side 161 of member 16 would effect interruption of the signal from light source 180 to cell 181.

The control circuit for motor 114 and clutch 115 is shown in FIG. 2. A primary switch 2 is closed by a cam 200 driven by cam shaft 20 at a time corresponding to the completion of knitting of one garment component. Such cam shaft would be actuated in accordance with the programmed cycle in a known manner. Closing of switch 2 simultaneously energizes light source 180, clutch 115 and solenoid 22 for closing normally open switch 220 to energize motor 114.

The signal means including light source 180 and photoelectric cell 181 constitute a secondary switch in the control circuit acting through amplifier 21 to maintain energization of solenoid 22 and clutch 115. Such secondary switch is closed by energization of light source 180 upon closing primary switch 2. If motor 114 is driven in a direction to move carriage 10 to the right as seen in FIGS. 1 and 2 until the edge 161 of blocking member 16 interrupts the light beam source 180, switch 180, 181 is opened to deenergize clutch 115 and solenoid 22 to open motor circuit 220, thereby stopping the carriage.

It would, of course, be satisfactory to mount the signalling device 180, 181 on stationary track 150 and to mount blocking member 16 on carriage 10. Alternatively, the photoelectric cell and light source may be mounted on the machine frame in horizontally spaced locations directed toward carriage 10 so that a light beam from the source 180 would strike a reflector strip to be reflected onto cell 181. In this instance the secondary switch would be opened as soon as the reflector strip moves into a position to reflect the light beam onto the cell. The light source and cell would be relatively moveable so that the position of the carriage in which the reflector strip actu-

ates the cell can be altered. It would also be possible to locate one of members 180 and 181 of the signalling device on the carriage and the other on the stationary track 150, in which case the secondary switch would be opened when the light beam and the cell are shifted relatively so that the light beam shines on the cell.

If a limiting movement in both directions is to be made possible so that the carriage can likewise be moved either in one direction or the other, a second solenoid 22 would be connected in circuit with the first to reverse the polarity of motor 114 in a known manner. Alternate actuation of one or the other solenoid would be effected by moving double-throw switch 19 shown in FIG. 1. Such actuation of switch 19 could be effected manually, or automatically such as by limit switches actuated by the carriage in its extreme positions. Automatic reversibility of the carriage 10 would be desirable, for example, to reset the carriage for later operation.

In FIG. 6 a modified form of the signal-blocking member 16 is shown. In this instance slides 163 and 164 are mounted in a groove 165. The positions of the slides can be adjusted by sliding them in such groove and then fixing their positions by bolts or set screws 166 in slots 167. Calibration 168 on the slides can be set relative to indexes on member 16 to determine the proper location of the slides in their groove. The projecting ends of slides 163 and 164 rather than edges 160 and 161 of member 116 would effect blocking of the light beam signal onto the photoelectric cell. If desired, screws 166 may have eccentric shanks so that the slides would be moved along groove 165 simply by turning the screws. Such auxiliary slides may utilize a scale having finer calibrations than the scale on track 150, or such slides may be calibrated for adjustment corresponding to the different needle sizes.

FIGS. 3, 4 and 5 show alternative types of devices for receiving nonmechanical signals which may be used in place of the photoelectric mechanism previously described, and companion devices for generating and emitting nonmechanical signals capable of being received by such receiving devices. In FIG. 3 a nozzle 24 directs an air jet into cylinder 240 for holding piston 241 in the upper position shown so that the free end of the piston rod 242 engages a switch arm 243 to hold it in engagement with the upper switch contact. When the air stream is interrupted by the blocking member 16 spring 244 presses the switch arm into engagement with the lower contact to energize motor 114 and clutch 115. The blocking member 16 could be mounted for movement with the carriage if desired. Naturally with a corresponding formation of the air pipes, suction can be used to control the switch arm 243.

In FIG. 4 a split ring electromagnet 23 produces a magnetic field including an eddy flow adjacent to its ends. Closing of the primary switch 2 energizes the field-inducing winding 230 in place of light source 180. Current induced by transformer effect in the secondary winding 231 closes the secondary switch 55 of the control circuit. When the blocking member 16 interrupts the eddy field 232, secondary winding 231 is deenergized and the secondary switch is opened to deenergize the motor and clutch.

The light source, photoelectric cell and blocking member of FIG. 1 may be replaced by a photoelectric counter such as shown in FIG. 5. A disk 3 keyed to the shaft of feed screw 1 includes a circular row of apertures 30. Preferably, the spacing of two adjacent apertures corresponds to the distance of two adjacent needles in a row transversely of the knitting frame, so that carriage 10 will move a distance corresponding to the spacing between two adjacent needles while disk 3 is indexed between adjacent apertures 30.*

It is also possible to provide a greater number of apertures 30 being in an integral ratio to the number of needles.

A light source 180 is located on one side of disk 3 and photoelectric cell 181 is located on the opposite side of the disk so that the light beam is directed parallel to the axis of rotation of the disk and is spaced from such axis a distance equal to the radius of the circular row of apertures 30. As the

disk rotates with screw 1, the light beam to the photoelectric cell is interrupted periodically to transmit signal pulses through cell 181 and amplifier 21 to counter 216. The counter will in turn actuate the multiple-switch bank 217 to energize and deenergize clutch 115 in accordance with a preset program stored in the counter 216 by means of punch cards or magnetic tape, for example*.

*Thus, the number of signal pulses caused by the rotation of the screw 1 is a measure of the setting distance. It is therefore of no importance how often the disk 3 rotates with the feed screw 1 during the setting of the stops 102.

Instead of apertures 30, disk 30, disk 3 may have slits or peripheral notches or reflector plates spaced circumferentially of the disk. In the last mentioned case the light source 180 would be on the same side of the disk as cell 181.

The precise location of the apertures in disk 3 can be set to correspond to the spacing of the needles by providing a second disk adjacent to and coaxial with disk 3, so that one disk is provided per setting direction. By turning the disk against the corresponding setting direction, the apertures 30, slits or peripheral notches are also moved in this direction and the interruption point for the setting movement of carriage 10 is corrected.

Alternatively, the counter control device could be used with the signal device shown in FIG. 1. In this case the blocking member 16 would be elongated and would have a serrated edge which would pass between the light source 180 and cell 181 to produce the pulsating light signals to the cell.

Carriage 10 can be actuated by the control circuit shown in FIG. 7 to set thread-guide stops 102 at the beginning of knitting of each of successive dissimilar garment components, such as a sweater front, back and two sleeves. In this case a machine operator could set all of the carriage stops initially and the knitting machine could continue to knit complete sets of such components for garments continuously until the number of garments desired has been produced without further attention by the operator. In this case blocking member 16 might be mounted on the carriage and several signalling devices 180, 181 could be mounted in various locations along track 150, for example. The number of signalling devices would correspond to the number of components for a complete garment.

Alternatively, a number of sets of tracks 150, blocking members 16 and signalling devices 180, 181 can be provided corresponding to the number of components of the garment. The control circuit for such signalling sets is shown in FIG. 7. The primary switch for this circuit is a four-contact stepping selector switch 190, the contacts of which are connected respectively to light sources 180, 183, 185 and 187. Photoelectric cells 181, 184, 186 and 188 are connected in parallel to energize motor 114 and clutch 115 through amplifier 121. The four light sources and cells move with the carriage relative to the respective tracks 150, 151, 152, and 153 each time carriage 10 moves, but only one of the light sources will be energized at a time corresponding to the position of switch arm 190.

After the completion of one garment component, switch arm 190 would be moved to engage the next adjacent contact to actuate the next light source in the series. After the four components have been made, switch arm 190 can be automatically reset to engage the first contact and the complete cycle can be repeated. The initial setting for the first garment component is made on track 150, the initial setting for the second component is made on track 151; the initial setting for the third component is made on track 152; and the initial setting for the fourth component is set on track 153. The multiple tracks and photoelectric signalling devices could also be used to control a digital counter 216, such as described in connection with FIG. 5.*

So that only a complete set of components for garments can be preset, when the setting of the carriage 10 continuously occurs in the same direction, in place of a single switch 19 being provided in series with the switch arm 190 there can be four switches connected in series with the switch arm 190, in order to establish the desired setting direction.

Hunting mechanism for automatically correcting the carriage position in case of overtravel is shown in FIG. 8. Two photoelectric cells 181 and 182 are mounted in carriage bracket 18 to be energized by the light source 180. In this instance, the servomotor 116 is energized by the direct current sources 212. The polarity of field winding 117 for the servomotor is set initially by the double-pole, double-throw switch 215 which switch can be controlled by the switch 19 shown in FIG. 1. Photoelectric cells 181 and 182 control a motor-reversing and shutoff mechanism 214 which, in turn, energizes and deenergizes or reverses the polarity of amplifier 213 completing the motor circuit.

Switch 19 will be set to energize motor 116 to turn in the desired direction for moving carriage 10 towards blocking member 16 when a primary switch, such as switch 2 shown in FIG. 2, is engaged to close the control circuit. Closing of the control circuit will effect energization of light source 180, and motor 116 will be energized simultaneously to drive the carriage in the direction set by switch 215.

If the carriage carrying light source 180 and cells 181 and 182 is actuated by switch 215 to move to the right as seen in FIG. 8 toward blocking member 16 which is initially in the full-line position, the left end of member 16 will first interrupt the light beam to deenergize cell 181 while cell 182 remains energized. Deenergization of one of the two cells 181 or 182 will effect deenergization of amplifier 213 and motor 116.

If the inertia of the motor causes the carriage to overtravel beyond position 16' indicated by dot-dash lines into the broken line position 16'', both cells 181 and 182 will be deenergized to effect reversal of the motor circuit polarity and reenergization of motor 116 to drive the carriage to the left until it reaches position 16' and cell 182 is again energized, at which time the motor will again be deenergized. If the carriage 35 should again overtravel, this time toward the full-line position of member 16, so that both cells 181 and 182 are energized, the motor circuit polarity will again be reversed through the reversing action of mechanism 214 and the motor energized to drive the carriage to the left. This hunting process will continue until the carriage stops in an equilibrium position with the blocking member in position 16'.

A similar hunting process could be effected by replacing blocking member 16 with a counter 3, 30 such as shown in FIG. 5 and providing two photoelectric cells 181 and 182. In this case the counting mechanism 3, 30, 180, 181, 182 would be connected to operate a digital control for mechanism 214 and amplifier 213 in which the actual travel of the carriage would be compared to a programmed path.

In the forms of the present invention discussed above, a clutch 115 has been shown to be disengaged and thereby eliminate the inertial effect of the motor contributing to carriage overtravel. Since the armature of the servomotor is the main source of inertial force when a control system for the motor circuit of one of the forms described above is used, provision of a servomotor armature having a very small moment of inertia could be used, such as a printed circuit motor or a shaded-pole motor in which case the clutch 115 could be omitted.

We claim:

1. In thread-guide setting mechanism for straight-bar knitting machines having a frame, a rotatable feed screw, thread-guide stop means, a reciprocable carriage carrying the thread-guide stop means and movable relative to the frame by rotation of the feed screw for locating the thread-guide stop means in a predetermined respective starting position when starting knitting of each selected garment component in knitting successively a series of garment components by the knitting machine, deenergizable drive means for driving the feed screw, and switch means operable to effect deenergization of the drive means, the improvement comprising signal-emitting means, signal-receiving means operable to receive a signal from said signal-emitting means and operable by predetermined alteration in the signal received to actuate the switch means for deenergizing the drive means, and control

means moved automatically in response to movement of the carriage to a predetermined position corresponding to the predetermined starting position of the carriage and thread-guide stop means to effect such predetermined alteration in the signal received by said signal-receiving means as to cause the signal-receiving means to actuate the switch means for deenergizing the feed screw drive means to stop the carriage and thread-guide stop means in such predetermined position.

2. In the setting mechanism defined in claim 1, the signal-emitting means being a light source and the signal-receiving means including a photoelectric cell.

3. In the setting mechanism defined in claim 1, the control means effecting movement of the signal-emitting means and the signal-receiving means from a relationship out of registry with each other into a relationship in registry with each other to effect such predetermined alteration in the signal received by the signal-receiving means.

4. In the setting mechanism defined in claim 1, mounting means mounting the signal-emitting means and the signal-receiving means in relatively fixed spaced relationship, signal-blocking means receivable between the signal-emitting means and the signal-receiving means, and the control means including means for effecting relative movement between said mounting means and said signal-blocking means in response to movement of the carriage and thread-guide stop means to effect such predetermined alteration in the signal received by the signal-receiving means by interposition of the signal-blocking means between the signal-emitting means and the signal-receiving means.

5. In the setting mechanism defined in claim 4, the signal-blocking means being carried by and adjustable relative to the frame, and the mounting means being mounted for movement conjointly with the carriage.

6. In the setting mechanism defined in claim 5, elongated track means mounted on the frame and including calibrations along its length, the signal-blocking means being mounted on said track means and adjustable relative to said track means calibrations.

7. In the setting mechanism defined in claim 2, signal-blocking means including a disk mounted for rotation with the feed screw and having alternate light-transmitting and light-blocking portions arranged in a circular row aligned with the light source and photoelectric cell, rotation of said disk relative to the light source effecting transmission of pulsing signals to the photoelectric cell.

8. In the setting mechanism defined in claim 7, the signal-receiving means including programmed digital computer means connected to receive the pulsing signals from the photoelectric cell and operable in response to such pulsing signals to actuate the switch means.

9. In the setting mechanism defined in claim 8, the programmed digital computer means including a plurality of programmed digital computers, and selector switch means operable to connect the photoelectric cell and said digital computers sequentially.

10. In the setting mechanism defined in claim 2, the signal-emitting means including a plurality of light sources and the signal-receiving means including a plurality of photoelectric cells corresponding, respectively, to said light sources, a plurality of signal-blocking members interposable, respectively, between said light sources and their corresponding photoelectric cells, an elongated track for each of said signal-blocking members, each of said signal-blocking members being adjustable along its track independently of the adjustment of any of the other signal-blocking members, and selector switch means operable to energize said light sources sequentially.

11. In the setting mechanism defined in claim 1, the signal-emitting means including an air jet nozzle projecting an air jet therefrom, and the signal-receiving means including a cylinder and a piston received therein and located in the path of the air jet to be positioned in said cylinder by the force of the air jet acting thereon.

12. In the setting mechanism defined in claim 1, the signal-emitting means including magnetic field-producing means, and the signal-receiving means including a coil in which an electric current is induced by the magnetic field produced by said magnetic field-producing means.

13. In the setting mechanism defined in claim 1, the deenergizable drive means including a motor and a dog clutch interposed between said motor and the feed screw.

14. In thread-guide setting mechanism for straight-bar knitting machines having a frame, a rotatable feed screw, thread-guide stop means, a reciprocable carriage carrying the thread-guide stop means and movable relative to the frame by rotation of the feed screw, ratchet wheels rotatable with the feed screw, and pawls cooperating with said ratchet wheels for effecting intermittent adjustment of the carriage during running of the knitting machine in opposite directions from a starting position when starting a garment component to a finishing position when such component is finished and the machine is stopped for setting the thread-guide stop means by a continuous rotation of the feed screw to locate the carriage in the starting position for the next garment component, and deenergizable drive means for the feed screw, the improvement comprising means for generating a nonmechanical signal, means for receiving such nonmechanical signal when the starting position for the next garment component is reached by the carriage, and control means operable by said means for receiving the nonmechanical signal to effect deenergization of the drive means when the carriage has reached such starting position for the next garment component.

15. In the thread-guide setting mechanism defined in claim 1, the signal-emitting means including light-emitting means, and the signal-receiving means including light-sensitive means.

16. In the thread-guide setting mechanism defined in claim 1, the signal-emitting means including fluid stream-emitting means, and the signal-receiving means including fluid pressure-responsive means.

17. In the thread-guide setting mechanism defined in claim 1, the signal-emitting means including magnetic field-producing means, and the signal-receiving means including magnetic field-actuated means.

18. In a fully-fashioned, multi-head, straight-bar knitting machine including fashioning means for shaping knitted garment blanks comprising fashioning rails and selvedge control screw means for controlling movement of said fashioning rails, the improvement comprising control means for automatically controlling sequential knitting processes by controlling racking in and racking out of the selvedge control screw means, said control means comprising a movable member movable lengthwise of the selvedge control screw means and controlled thereby, a power source for driving the selvedge control screw means, means for energizing said power source after each completed phase of a sequential knitting process so that said movable member is moved by the selvedge control screw means in one of two opposite directions to a new starting position, a plurality of photosensitive cells, light source means for illuminating said photosensitive cells, means for controlling illumination of said cells by said light source means, means for mounting said cells and said illumination-controlling means so that one moves conjointly with said movable member and the other is relatively fixed, the relative movement of said illumination-controlling means and the corresponding photosensitive cell varying the illumination of said cell by said light source means, and electric circuit means responsive to an electrical signal produced by varying the illumination of said photosensitive cells for controlling said power source to cause termination of movement of said movable member.

19. The knitting machine defined in claim 18, in which the power source includes an electric motor and an electromagnetic clutch operatively connecting said electric motor and the selvedge control screw means.

20. The knitting machine defined in claim 18, each of the photosensitive cells being mounted on a movable support means slidably engaged with a relatively fixed slide rail.

21. The knitting machine defined in claim 20, fixed width-setting indexes in association with the respective photosensitive cells, including horizontally disposed calibrated rules and including width-setting blocks individually adjustable along said rules, each of said width-setting blocks having light-beam intercepting plate means.

22. The knitting machine defined in claim 21, and brackets carried by the fixed slide rail and carrying the width-setting in-

dexes.

23. The straight-bar knitting machine defined in claim 18, electrical circuit means for the photosensitive cells including a plurality of program selectors for the respective photosensitive cells, each of said program selectors having a control switch for determining the direction in which the selvedge control screw means drives a movable member, and circuit-selector means for selecting the proper control switch to effect movement of the desired photosensitive cell and in the desired direction and to activate such desired photosensitive cell.
